Roland E. Doeden, Crete, Ill., assignor to Mall
Tool Company, Chicago, Ill., a corporation of
Illinois

Application June 6, 1951, Serial No. 15,429

Term of patent 14 years

(Cl. D54—14)

To all whom it may concern:

Be it known that I, Roland E. Doeden, a citizen of United States, residing at Crete, in the county of Will and State of Illinois, have invented a new, original, and ornamental Design for a Power Tool Unit, of which the following is a specification, reference being had to the accompanying drawing, forming part thereof.

Figure 1 is a side elevational view of a power tool unit, showing my new design;

Figure 2 is a top plan view of the unit;

Figure 3 is an end elevation view taken looking toward the handle of the tool unit.

The side not shown is substantially like the side shown.

I claim:

The ornamental design for a power tool unit, substantially as shown and described.

ROLAND E. DOEDEN.
